UNITED STATES PATENT OFFICE

130,000

DESIGN FOR A REFRIGERATOR CABINET

Raymond Loewy, New York, N. Y., assignor to
General Motors Corporation, Dayton, Ohio, a
corporation of Delaware

Application July 17, 1941, Serial No. 102,205

Term of patent 14 years

To all whom it may concern:

Be it known that I, Raymond Loewy, a citizen of the United States, residing at New York city, in the county of New York and State of New York, have invented a new, original, and ornamental Design for a Refrigerator Cabinet, of which the following is a specification, reference being had to the accompanying drawings, forming part thereof.

In the drawings:

Fig. 1 is a front elevational view of the refrigerator cabinet, showing my new design;

Fig. 2 is a side elevational view of the refrigerator cabinet;

Fig. 3 is a top plan view of the refrigerator cabinet;

Fig. 4 is a front perspective view of the refrigerator cabinet;

Fig. 5 is a sectional view of a portion of the refrigerator cabinet taken on the line 5-5 of Fig. 3 and in the direction of arrows; and

Fig. 6 is an enlarged sectional view of a portion of the refrigerator cabinet taken on the line 6-6 of Fig. 1 and in the direction of the arrows.

I claim:

The ornamental design for a refrigerator cabinet, as shown.

RAYMOND LOEWY.
